UNITED STATES PATENT OFFICE.

JOHN C. GARAND, OF SOMERSET, MARYLAND.

AUTOMATIC GUN.

Application filed September 5, 1919. Serial No. 321,956.

This invention relates to improvements in automatic firearms and more especially to that class of automatically loading firearms in which the forces derived from the explosion of the cartridge are utilized to expel the spent cartridge and reload the piece for another shot.

The object of this invention is to provide a rapid firing arm which is composed of few parts of simple construction, readily adapted for production in large quantities, light and transportable, easily assembled and disassembled, and which is capable of being fired either singly or with repeated automatic action at the will of the operator.

The present invention differs in several essential points from my prior invention as set forth in application filed July 11, 1919 bearing Serial No. 310,249. In the prior application mentioned, the gun mechanism is so designed and constructed as to utilize the power of the primer to actuate the automatic parts. Experiments have shown that there is a wide variation in the amount of power produced by primers utilized in various standard makes of cartridges, and this is true even in cartridges which have approximately the same ballistic properties. It is obvious that the continuous operation of an automatic machine gun that depends alone upon the force from the primer, is liable to be interrupted if one primer should fail to deliver the force required to actuate the mechanism throughout its cycle. Furthermore it has been demonstrated with this type of gun that delicate and troublesome adjustments in the relative masses and tension means of the actuating mechanism are necessary, in order to compensate for varying amounts of force derived from the primers of standard cartridges. Therefore in the improved type of gun embodied in the present invention a novel breech mechanism is provided, which mechanism utilizes a combination of forces derived from the explosion of the cartridge, which forces may be enumerated as follows: The recoil of the gun, the limited rearward movement of the cartridge in confined position, the rearward movement of the primer

relative to the cartridge, and the rearward movement, or "blow back" of the cartridge after becoming released from the firing chamber.

It will, therefore, be observed that the present invention involves improvements in the general construction of firearms which improvements, in combination with means for actuating the mechanism of an automatic machine rifle, will permit the interchangeable use of standard makes of cartridges without requiring adjustments and which will provide further advantages as will hereinafter appear.

One feature of this invention is a provision of a specific breech mechanism in which the cartridge is inserted into the gun barrel at the instant of firing, thereby eliminating the danger of accidental explosion which is likely to occur in rapid firing rifles when the cartridge is allowed to even momentarily remain in the explosion chamber when the gun has become heated to a degree sufficient to cause a spontaneous combustion of the explosives in the cartridge.

Another feature of this invention relates to a novel actuator and breech bolt so co-acting as to insure the positive operation of the firing pin in exploding the cartridge, and also permitting operation of the actuator and bolt by the firing pin, in the manner to be hereinafter described.

Another feature of this invention relates to a novel construction of the trigger mechanism, which positively controls the automatic action of the gun, whereby it may be fired either singly or repeatedly, by a simple manipulation of the trigger.

Another feature of this invention relates to a novel construction of the receiver and stock bracket, which allows the entire receiver and barrel, with their associated parts, to be readily separated from the stock bracket and associated parts, by a simple manipulation of a single locking bolt.

Another feature relates to a novel construction which permits the moving parts of the rifle mechanism to be easily disassembled and assembled by hand, without the use of tools of any kind.

Another feature of this invention relates to a novel and simple construction of the extractor.

Another feature of this invention relates to the provision of a barrel locking means forming a "scoop" or guide for introducing the cartridges into the explosion chamber.

The invention consists in certain novel features of construction and arrangement of parts as will be hereinafter described and pointed out in the claims.

Figure 1 shows the longitudinal cross section of the rifle in cocked position.

Figure 2 shows the longitudinal cross section of the rifle at the instant of firing, with the trigger mechanism held in position for repeated firing.

Figure 3 is a longitudinal cross section of the gun showing the position of the breech mechanism immediately after the gun is fired with the trigger mechanism in position for a single shot.

Figure 4 is a top plan view of the receiver or casing.

Figure 5 is a bottom plan view of the receiver or casing.

Figure 6 is a rear view of the receiver or casing.

Figure 7 is a fragmentary detailed view of the rear end of the barrel, and locking means therefor.

Figure 9 is a top view of the breech bolt.

Figure 10 is a bottom view of the breech bolt.

Figure 11 is an enlarged fragmentary, detailed cross-sectional view of the breech bolt, showing the extractor and the ejector in operative engagement with a cartridge.

Figure 12 is a front view of the breech bolt with part of the cartridge shown in section.

Figure 13 is a rear view of the breech bolt.

Figure 14 is a detailed view of the extractor.

Figure 15 shows the side elevation of the trigger mechanism frame and cartridge ejector.

Figure 16 is the front view of the trigger mechanism frame and cartridge ejector.

Figure 17 is a fragmentary view in elevation of the left hand side of the rifle.

Figure 18 is a fragmentary view, in elevation of the right hand side of the rifle.

Figure 19 is a detailed view of the assembly locking bolt.

Figure 20 is a cross section of assembly locking bolt taken on line 20-20 of Figure 19 and shown in three positions, namely: "ready", "safe", and "take-down" positions.

Referring to the drawings, the rifle embodying the present invention may be mounted on a gun stock 1 of the usual military type, with a stock bracket 2 seated

therein and secured by suitable bolts 3 and 4. The stock bracket 2 comprises a trigger guard 5, an elongated housing 6 adapted to receive the trigger mechanism 7, and a magazine compartment 8 adapted to receive a cartridge magazine 9 of any approved pattern containing a plurality of cartridges 10, 10, in position to be automatically supplied, one at a time, in the operation of the gun. A receiver 11, adapted to retain the reciprocating breech mechanism, is attached to the rifle barrel 13 by means of a threaded connection 14 as shown. The receiver and gun barrel are mounted on the stock bracket and detachably connected therewith by means of a T-slot 15 at the rear end of the receiver, the T-slot being engaged by the lug 16 extending upwardly from the rear end of the stock bracket, and by a lug 17 extending upwardly from the front end of the stock bracket, said lug 17 being adapted to engage a recess 19 in the receiver, and an adjacent recess 18 formed in the rear end of the rifle barrel 13 (see Figure 7). The rear face of said lug 17 is further provided with a cam surface 20, which forms a scoop to guide the cartridges into the explosion chamber 21 during the operation of the gun.

In mounting the receiver on the stock bracket, the receiver is brought into engagement therewith so that the T-slot 15 on the receiver engages the lug 16 on the stock bracket, and so that the lug 17 is positioned in the recess 18 in the rifle barrel, and recess 19 in the receiver: then by turning the bolt 12, (see Figures 19 and 20) the cam 12^a engages with the notch 11^a of the receiver and locks the receiver against end-wise movement on the stock bracket. With the receiver and barrel thus locked in place on the stock bracket, said lug 17 serves to check the recoil of the barrel and receiver, also retains the receiver on the stock bracket and locks the barrel against unscrewing from the receiver. The receiver may be unlocked by turning the bolt 12 to the "take-down" position (see Figure 20) in which a flattened portion 12^b of the cam 12^a allows the receiver to be withdrawn forwardly from engagement with the stock bracket.

The bolt 12 also acts as a lock for the actuating mechanism as will hereinafter be described.

The main elements of the reciprocating breech mechanism are mounted in the receiver 11 and comprise a breech bolt 22 which is rotatably locked in a forward position in the receiver, an actuator 23 slidably but non-rotatably mounted in said receiver and having considerable mass in relation to said bolt, and a main operating spring 24 in the rear end of said receiver, normally under compression tending to force the actuator and bolt towards the front end of the receiver. The breech bolt is locked and un-

locked, to confine a cartridge in the firing chamber 21, in the following manner: The bolt is provided with a rearwardly extending portion 22^a, projecting into a suitable recess 23^a in the actuator, and carries a pair of laterally extending lugs 25, 25 adapted to engage in camways 26, 26 on the actuator, said lugs and camways being so constructed as to rotate the bolt as the bolt moves longitudinally in the actuator. The forward portion, or bolt head 22^b, of the breech bolt 22 is provided with a plurality of locking lugs 27, 27 on opposite sides thereof, adapted to enter recesses 28, 28 formed between lugs 28^a, 28^b in the front end of the receiver, and a guide fin 29 which moves in the longitudinally extending groove 30, in the top wall of the receiver. While the bolt is in locked position in the front of the receiver, and the locking lugs 27, 27 are engaged in the recesses 28, 28, the actuator and bolt occupy a position in relation to each other as shown in Figures 2 and 8, in which the lugs 25, 25 on the bolt are in their rearmost position in camways 26, 26 on the actuator, and the guide fin 29 is in an offset portion 31 of the groove 30. The actuator 23 is held in forward position by tension of a spring 24, and at the instant of explosion of the cartridge is caused to be moved rearwardly in a manner to be presently described.

As the actuator moves away from the locked breech bolt, the latter is rotated by the action of the lugs 25 in the camways 26, 26 so as to move the locking lugs 27, 27 out of locking engagement with the recesses 28, 28 of the receiver, and also move the guide fin 29 into the longitudinal portion of the guide groove 30.

It will be observed, however, that the actuator moves a short distance rearwardly before the bolt begins to be rotated, and the unlocking action of the bolt is therefore delayed momentarily after the cartridge is fired. This is because of the shape of the camways 26, 26 (see Figure 8) which allow the actuator to move a substantial distance irrespective of the bolt, additional movement of the actuator being operative to cause the lugs 25, 25 to engage the inclined guideways and rotate the bolt out of locked position. The amount of rotation of the breech bolt is limited by the guide fin 29, which allows the sufficient rotation of the bolt to unlock the lugs 27, 27 but does not allow the lugs 25, 25 to move out of the open ends of camways 26, 26. It will thus be seen that the actuator serves to unlock the bolt and to carry it rearwardly. Similarly as the actuator and bolt are returned to their forward position, the breech bolt is again rotated by the action of the camways 26, 26 into locked position.

The locking lugs 27, 27 are provided with

inclined surfaces 27^a, 27^b which engage with lugs 28^a, 28^b on the receiver at such a degree of inclination to the axis of the bolt as to form therewith the angle of repose, i. e., the maximum angle in which the friction between the locking surfaces retains the locking lugs in engagement against the force of explosion, but in which a minimum of power from the cam action of the actuator is required to overcome this friction, and to unlock the bolt. I have experimentally determined this angle of repose to be approximately 83 degrees, but this may vary somewhat according to the smoothness of the engaging surfaces or the amount of lubrication of the parts.

The actuator 23 is provided with a finger piece 23^a, (see Figure 18) extending from the right side of the receiver 11, and moving in recess 11^a, formed in the bottom wall of said receiver for the purpose of retracting the actuator by hand when it is desired to cock the piece. A rearwardly extending shield 23^b is attached to said actuator, serving to close the rear end of the recess 11^a against access of rain, dirt, or other foreign matter.

In the construction above described, it will be observed that one source of power for actuating the gun mechanism is provided by the recoil of the gun. Experiments have shown that the recoil of a rifle weighing approximately ten (10) pounds and firing a standard U. S. cartridge, gives a rearward acceleration to the mass of the gun amounting to approximately twelve (12) feet per second. This rearward acceleration affects the whole mass of the gun, but the rearward movement of the gun is checked by the shoulder of the operator, or other supporting means, in the usual manner.

The actuator 23, however, being in unlocked relation to the gun, is free to move rearwardly against the main operating spring 24, and to exert thereagainst the momentum imparted to its mass by the recoil, to start the actuating mechanism in operation. The amount of force derived by the actuator from this source is relative only, and depends upon the rapidity with which the acceleration of the gun itself is retarded and overcome by the shoulder of the operator, or other supporting means; but at all events, the force thus derived has been found to be of substantial assistance, in combination with other forces hereinafter disclosed, to provide energy for actuating the automatic mechanism.

The mechanism for utilizing the power derived directly from the explosion of the cartridge comprises a firing pin 32 in the bolt head 22^b. Said firing pin is preferably provided with a striking face 32^a, sufficiently large to engage the entire area of a standard cartridge primer, and having a

firing point 32^b, in the center thereof. The firing pin is further provided with a flanged portion 33, which engages a shoulder 34 in the breech bolt to limit rearward movement therein, forward movement being limited by an annular ring 35 seated in the face of the bolt, as shown. The bolt, firing pin, and firing chamber 21 are so constructed that when the bolt is rotated to locked position, 10 the cartridge is not pushed to its innermost position in the firing chamber, but is moved a short distance further therein by the firing pin as the gun is fired.

The gun mechanism is held in cocked position as shown in Figure 1 with the actuator and bolt retained in a retracted position in the rear end of the receiver. In this position the actuator is spaced from the rear end of the firing pin and held by a sear 44, 15 as will be described. When the sear is released, the actuator and bolt are moved forward by the spring 24, and as the bolt is being rotated to locked position as hereinbefore described, the forwardly extending portion 23^b of the actuator approaches the firing pin 32 and forces it against the primer 10^a of the cartridge 10, as shown in Figure 2. Owing to the construction of the firing chamber and bolt, as above described, the entire cartridge will be forced by the firing pin to its innermost position in the firing chamber, forming a head space between the bolt and the cartridge before the primer is detonated by the firing pin. The subsequent 20 explosion of the cartridge, as is well known, generates a large pressure of gas in the firing chamber, which expels the projectile through the rifle barrel and at the same time tends to force the cartridge rearwardly 25 against the breech bolt. The cartridge will therefore be thrown rearwardly through the head space between the bolt and cartridge until it is checked against the locked breech bolt. The firing pin, being in contact with 30 the primer, will be thrown rearwardly with the cartridge, and the impulse of this movement is transmitted through the firing pin to the actuator, and serves to give it a rearward acceleration which is utilized to unlock the bolt and further actuate the mechanism.

The purpose of this novel construction which utilizes the limited movement of the cartridge while the bolt is in locked position is as follows: It is a well known fact that those military types of cartridges having a reduced portion at the forward end of the cartridge case cannot be immediately withdrawn from the explosion chamber after firing, because of the danger of bursting the cartridge case. Consequently, it has heretofore been the usual practice to rigidly secure the cartridge in its place by retaining the breech bolt in its locked position 40 until the pressure in the explosion chamber

has become sufficiently reduced to allow the cartridge to be safely withdrawn. However, I have experimentally demonstrated that the cartridge may be allowed to move rearwardly a limited distance at the instant of 70 explosion, without danger of bursting or otherwise injuring the case, provided the rearward movement does not exceed approximately .015 of an inch. I have, therefore, provided the above described construction to utilize the direct force of this movement, which force, if the cartridge were securely locked against movement, would be transmitted directly to the body of the rifle. I have found that the best results are obtained by allowing a head clearance of approximately ten one thousandths (.010) of an inch between the cartridge and the bolt after it is locked. The importance and magnitude of this impulse, or acceleration, 80 though carried through but a short distance, is more readily understood when it is pointed out that the standard U. S. cartridge has been found by experiments to exert a force of approximately 12,000 lbs. on the breech bolt at the instant of firing.

The construction herein described also affords a further source of power for utilizing the forces of the gases generated in the firing chamber, after the movement of the cartridge has been checked against the locked bolt. This source is derived from the limited rearward movement of the primer in excess of its movement with the cartridge. As has been above described, the limited rearward movement of the cartridge case and primer transmits an impulse to the actuator through the firing pin. The gas pressure generated in the cartridge, however, is amply sufficient to force the primer beyond its normal position in the cartridge, after the movement of the cartridge has been checked by the bolt. Consequently the firing pin 32 is so arranged that it may be moved rearwardly by the primer through an additional distance into the face of the breech bolt, (see Figure 3) thereby affording an additional acceleration to the actuator. The rearward movement of the primer and firing pin is limited by the shoulder 34 as shown in Figure 3, as it has been found inadvisable to allow the primer to come out of the cartridge before the firing pin is brought to rest. It will be observed that the face 32^a of the firing pin is so dimensioned as to be of approximately the same diameter as the cartridge primer illustrated, yet it is obvious that the face of the firing pin may be made substantially larger in diameter than the primer without materially affecting the action of the respective parts. I have demonstrated that many different makes of cartridges, having varying sized primers, can be used with uniform success in my rifle, without necessitating any change in the con- 125

struction of the firing pin, or associated parts.

A still further source of power for actuating the gun mechanism is derived from the rearward movement of the cartridge case after the breech bolt becomes unlocked by the action of the actuator. This force is commonly known as the "blow back" and is operative during the time that the reduced portion at the forward end of the cartridge is in contact with the corresponding reduced portion of the explosion chamber in which the cartridge is adapted to fit. In the present invention this force is utilized as an auxiliary to the before mentioned forces in operating the moving parts.

I find that it is necessary that the reciprocating parts which receive energy from the force derived from the explosion as described, should have a certain minimum weight in order that they may accumulate energy sufficient to carry out the operations of ejecting the cartridge and inserting a fresh one, and to overcome the friction of the parts in passing through a cycle of operations. Also the spring must be capable of storing sufficient energy to return the reciprocating parts from their rearmost position to the cocked position, and to force the parts home to locked and firing position. I have found by experiments that good results are obtained when the actuator weighs about $1\frac{1}{4}$ lbs. and the spring is of spring wire (.073 in. diameter) coiled into a helix about 10 inches long when uncompressed. These values may be changed somewhat depending upon the ballistic properties of the cartridge used, or when it is desired to vary the speed of the operation of the gun.

The mechanism for extracting the expanded cartridge from the firing chamber and ejecting the same from the rifle, comprises a laterally movable extractor 36, mounted in a socket 36^a, formed in the front face of the bolt head 22^b. Said socket is provided with undercut walls adapted to retain the laterally extending flanges 38 on the extractor so constructed as to permit a retaining lip 39, formed on the extractor, to be moved into engagement with the cartridge flange 10^b. Said flange 10^b is adapted to fit into a recess 37 formed in the front face of the bolt head 22^b. (See Figures 11, 12 and 14.) A small compression spring 37^a tends to retain the extractor in position to engage with the cartridge flange. The extractor and spring may be inserted in the recess 36^a while the retaining ring 35 is out of its position in the bolt head. When the retaining ring is replaced, the extractor abuts the edge of the ring and is held in position as shown. In order to allow for the limited movement of the cartridge in the firing chamber after the bolt becomes locked, it is necessary to provide for a small amount of

end-wise movement of the cartridge flange under the retaining lip 39, as is indicated at 39^a (see Figure 11). As the bolt forces the cartridge into position in the firing chamber, the cartridge flange becomes seated in the recess 37 and is engaged by the retaining lip 39 of the extractor. As the bolt becomes unlocked and moves rearwardly, the cartridge is drawn rearwardly therewith until the bolt reaches a position substantially as shown in Figure 1. At this instant a suitable finger 40, (see Figure 11) formed integrally with the frame member 41 of the trigger mechanism, extends into the path of the cartridge case by reason of the incut 37^a, in the edge of the bolt, (see Figure 12) and comes into contact with the edge of the cartridge case at a point opposite the ejector as shown in Figure 11, so that the cartridge is flipped out of the recess 37, and is ejected from the aperture 42 formed in the side wall of the receiver.

A pair of flanges 43, 43 extend upwardly from the stock bracket into the rear end of the receiver for the purpose of retaining the operating spring 24 in longitudinal position.

I have provided a series of grooves 11^b, 11^b, extending longitudinally in the interior walls of the receiver, which grooves serve to facilitate the conductance of heat generated in the rapid firing of the rifle and also to lighten the construction of the gun.

The automatic trigger mechanism 7 is seated in a suitable housing 6 in the stock bracket and comprises a trigger frame 41, a sear 44 and trigger 45. Said sear 44 is mounted on a pivot pin 44^b, and has limited longitudinal movement thereon by reason of the slot 44^a. A suitable spring 46 is provided, so positioned as to normally force the sear rearwardly and upwardly, into engaging position with the detent or catch 23^c on the actuator. The trigger 45 comprises a rocking arm pivoted on pin 45^a having a sear-engaging head 46 which extends through an aperture 47 between the ends of the sear, and is adapted to engage the top surfaces 48 or 49, depending upon whether it is desired to hold the sear in position to permit the gun to fire a single shot or to fire repeatedly, as will hereinafter be described.

In the position of the trigger mechanism shown in Figure 1, the gun is shown in cocked position with the detent or catch 23^c, of the actuator in engagement with the sear. In this position, the force of the main operating spring 24 is sufficient to overcome the force of the spring 46 of the sear and to force the sear to a forward position as shown, with the rear end of the trigger head 46 hooked over the surface 49 of the sear. As the trigger is pulled in the usual manner, the sear is depressed out of engagement with the actuator to fire the gun.

A trigger stop 51 at the control of the operator is provided, which normally limits the movement of the trigger, and while said stop 51 is in position as shown in Figure 1, 5 the sear can only be depressed sufficiently to release the actuator. At the instant the actuator moves forward, the force of the spring 46 acting on the sear is sufficient to throw the sear rearwardly to a position 10 shown in Figure 3, in which the surface 49 of the sear becomes disengaged from the trigger head 46, and is free to move upwardly into position to catch the actuator as it is thrown rearwardly, and to retain it in 15 cocked position. Therefore, in order to again fire the gun, it is necessary to fully release the trigger and to pull it anew. A small spring 45^a is so positioned as to force the trigger head upwardly and to return 20 the trigger to operating position, with the head 46 engaging with surface 49 of the sear. The slot 45^c of the trigger allows sufficient longitudinal movement of the trigger arm 45, on the pivot pin 45^a, to compensate for the corresponding longitudinal 25 movement of the sear 44.

When it is desired to allow the gun to function as a repeating rifle, the stop 51 provided in the trigger guard 5, is pushed 30 upwardly by the finger of the operator out of engaging position with the trigger, to the position shown in Figure 2. In this position the trigger may be retracted to its rearmost position, so that the front end 35 of the trigger head 46 engages with the surface 48 of the sear and holds the sear out of the path of the actuator, so long as the trigger is held in retracted position. When the trigger is released from retracted 40 position, a suitable spring 51^a carried by the stop 51, automatically returns the stop to its normal position, so that the rifle is converted into condition for firing single shots only. It will therefore be seen that the 45 operator can continue the repeated firing of the rifle until the trigger is released, at which instant the sear will again be forced upwardly in position to catch the actuator and to stop the firing of the gun.

50 The trigger frame also carries a magazine locking arm 52, pivoted on pin 53, and having a locking finger 54 adapted to engage in a suitable catch on the magazine to retain the latter in place. A second locking finger 55 on said arm 52, is adapted to engage a grooved portion 12^c on the assembly bolt 12, to lock the same against endwise movement. The spring 46, which serves to operate the sear, also maintains the locking arm 52 in locked position. Whenever it is desired either to take out the magazine 9, or to extract the locking bolt 12, the locking arm 52 may be released by manipulating a finger piece 52^a, preferably located 60 65 within the trigger guard.

The locking bolt 12 not only serves to retain the receiver in locked position on the stock bracket, as has been before described, but it is also provided with a cam portion 12^c which is so constructed as to engage a 7^c notch 56 in the bottom face of the actuator, when an indicating arm 57 carried by the bolt, is moved to "safe" position, as shown. This notch is so positioned that it cannot be engaged by the cam 12^c unless the actuator is 7^c in the furthest forward position, as shown in Figure 2, in which position the firing pin must extend beyond the face of the breech bolt. With such a construction, the actuator cannot be locked unless the firing 8^c chamber is empty. A series of markings, such as: "take-down", "safe", and "ready", or similar markings may be provided on the outside of the rifle as indicated in Figures 8^c 17 and 20 to show the three positions to 8^c which the locking bolt is adapted to be turned, as desired.

The operation of the rifle is as follows: The mechanism is cocked by drawing the finger piece 23^d rearwardly to a cocked position, as shown in Figure 1, with the actuator 23 under compression of the spring 24, but retained by the sear 44 in a rearward position in the receiver. As the trigger is pulled the sear is released and the actuator and bolt move forwardly, with the guide lug 29 of the bolt moving in the longitudinal groove 30 in the receiver, which construction holds the actuator and bolt head 22^b spaced apart because of the cam action between the 1^c lugs 25, 25 on the bolt and the camways 26, 26 on the actuator. As the bolt moves forward, a projection 58, on the bolt face engages the rear end of the cartridge 10 in the magazine and forces the cartridge forward 1^c out of the magazine and, guided by the scoop 20, adjacent the mouth of the firing chamber, the cartridge is forced upwardly and into the firing chamber by the breech bolt. As the breech bolt approaches the forward end of the receiver, the guide fin 29 reaches the off set portion 31 in the longitudinal groove 30, which frees the bolt for rotation in a clock-wise direction. The lugs 1^c 25, 25 on the bolt are now free to be rotated in the cams 26, 26 so as to bring the locking lugs 27, 27 into locking engagement with the recesses 28, 28 on the receiver, thereby firmly locking the bolt and confining the cartridge in the firing chamber. The actuator approaches the bolt head 22^b while the bolt is being rotated, and the camways 26, 26 on the actuator are so constructed as to allow the actuator to continue its forward movement a short distance after the bolt has ceased rotating and to engage the rear end of the firing pin 32 in the bolt head. The firing pin is then driven forward by the actuator to engage with the primer of the cartridge in the firing cham- 12^c 13

ber. Owing to the construction of the firing chamber as has been described, the cartridge is allowed to be moved forward by the primer a short distance before becoming 5 fully seated in said chamber, thereby forming a small clearance or head space between the face of the breech bolt, and the base of the cartridge at the instant that the cartridge is fired. The subsequent explosion 10 of the cartridge causes a generation of gas pressure in the firing chamber, which expels the projectile from the rifle barrel in the usual manner, and throws the cartridge case rearwardly against the face of the 15 breech bolt. As has been above described, a limited rearward movement of the cartridge is permissible, provided it does not exceed .015 of an inch. The construction of the firing pin is such that it engages with 20 the primer and, as the cartridge is thrown rearwardly, the force of this movement is transmitted rearwardly through the firing pin to the actuator. The rearward movement of the cartridge is checked by the face 25 of the locked breech bolt, but the primer 10^a of the cartridge is still under great pressure caused by the generation of gases in the firing chamber, which pressure is transmitted through the primer hole of the cartridge to such a degree as to force the primer 30 rearwardly from its normal position on the cartridge, as shown in Figure 2. This rearward movement of the primer is therefore a continuing force, acting on the actuator through the firing pin, tending to accelerate the actuator in a rearward direction. After the actuator has moved rearwardly a short distance, the lugs 25, 25 are rotated in the camways 26, 26 to unlock the 35 bolt. As the bolt is released, there is still a considerable amount of pressure in the firing chamber, which serves to blow the cartridge out of its position in the firing chamber, without however, having sufficient pressure 40 to damage the cartridge case as it is expelled therefrom. The expended cartridge case is held in the recess 37 of the breech bolt by means of the extractor 36 during the rearward movement of the bolt until the 45 ejector 40, fixed on the trigger mechanism casing 41, comes into contact with the rear edge of the cartridge casing as shown in Figure 11, and flips the expended cartridge out of the receiver. The actuator and bolt 50 continue their rearward movement, storing up sufficient energy in the spring 24 to return the actuator and bolt to locked and firing position. In single fire work the actuator is caught by the sear 44 during its rearward movement, and retained in cocked position as in Figure 1 ready to be fired again. The automatic repeating action of the rifle 55 is the same as above described except that the stop 51 is raised to permit the trigger 45 to depress the sear 44 out of the path of

the actuator, in which case the automatic action of the gun will continue until the magazine is exhausted, or the trigger is released so as to bring the sear back into position for engagement by the actuator.

The operation of disassembling the rifle is as follows: if there are any cartridges in the magazine, it is preferable, first, to manually withdraw the cartridge magazine 9 after releasing the magazine lock 54. The locking bolt 12 is then turned to the "take-down" position, as shown in Figure 20, and the cam 12^c will be disengaged with the notch 11^a on the receiver, thereby permitting the receiver and barrel to be pushed forwardly on the stock bracket to disengage the lugs 16 and 17 on the stock bracket. The receiver, barrel, and reciprocating breech mechanism can then be withdrawn from the stock bracket. The actuator and breech bolt will normally be retained in the receiver by means of the spring 24, which tends to hold them in locked relation at the front end of the receiver, but by pushing back the finger piece 23^d sufficiently to unlock the bolt, the actuator, bolt and spring may be dropped out of the receiver for inspection or cleaning, if desired. As the guide fin 29 is no longer held in the groove 30 of the receiver, the lugs 25, 25 on the breech bolt may now be rotated out of the open ends of camways 26, 26 so that the breech bolt is readily withdrawn from the actuator. The extractor 36 and the firing pin 32 may be removed from the breech bolt, if desired, by removing the retaining ring 35 which is preferably retained in place in the breech bolt by a press fit, so that it may be ejected therefrom by forcing the firing pin against its rear face. Therefore, when the entire breech mechanism is disassembled, it comprises but six (6) parts, namely: actuator, spring, breech bolt, firing pin, extractor and retaining ring. The assembly of these parts is equally simple, the only care necessitated being that of inserting the breech bolt in the actuator before placing the actuator in the receiver, and then insuring that the guide fin 29 is seated in the longitudinal groove 30, so that the lugs 25, 25 on the breech bolt cannot be rotated out of the open ends of the camways 26, 26 on the actuator.

The disassembly of the trigger mechanism from the stock bracket is equally simple. As has been described, the locking bolt 12 is rotated so as to allow the receiver to be pushed forward and disengaged from the stock bracket. The cam 12^c, which serves as a lock for the actuator, normally extends upwardly into the receiver so that the bolt 12^a cannot be withdrawn, or accidentally fall out of the gun as long as the receiver is in place on the stock bracket. However, after the receiver has been removed from the stock bracket, as above described, the

locking bolt 12 may be withdrawn by manipulating the locking arm 52 which disengages the locking finger 55 from the groove 12^a on the locking bolt. When the locking bolt 5 has been thus disengaged and withdrawn from the stock bracket, the entire trigger mechanism may be withdrawn by moving the same forward, out of engagement with the bolt 3, which extends transversely 10 through the trigger mechanism housing, as shown. The trigger mechanism, therefore, may be easily handled, inspected or cleaned as a unit, or if desired to further disassemble the mechanism, this is easily accomplished 15 by pushing out the sear pivot pin 44^b, the trigger pivot pin 45^a, and the locking arm pivot pin 53 which normally are retained in the trigger frame between the walls of the stock bracket but are free to be withdrawn 20 from the trigger frame when the trigger mechanism is not confined in the stock bracket. When the trigger mechanism is fully disassembled, it comprises nine (9) parts, namely: sear 44, sear spring 46, trigger 45, trigger spring 45^b, locking arm 52, pivot pins 44^b, 45^a and 53, and the trigger frame 25 41. It will, therefore, be observed that the entire gun can be disassembled for the purpose of cleaning, repairs, replacement or transportation, in a minimum of time, and in reassembling, the parts are so few and simple in construction that they are easily understood and replaced by even an unskilled operator. Furthermore, the rifle 30 5 may be "taken down", that is, separated into two major parts by dismounting the receiver from the stock bracket and yet the breech mechanism will be retained in the receiver and the trigger mechanism will be 35 retained in the stock bracket so that none of the moving parts will drop out of their respective positions unless positively disengaged and removed by the operator.

It will be observed that the entire mass 40 of the breech mechanism reciprocates substantially on a line with the axis of the rifle barrel, and that the locking action is by rotation on this axis, instead of any movement of parts transverse to the said axis. 45 This feature has been found to be a determining factor in the accuracy of firing, for it has been demonstrated with automatic rifles having any substantial part of the actuating mechanism moving either transversely 50 of the barrel axis, or even parallel to the axis, that such movement invariably tends to affect the accuracy of firing by throwing the piece out of predetermined alignment with the target when the gun is fired. In the 55 present construction, all movements of the breech mechanism are directly in line with and on the axis of the barrel, and therefore much greater accuracy is afforded than with other types of construction above mentioned.

As ordinarily constructed, the primers of

standard cartridges are provided with comparatively thin side walls, so that the primer is liable to be distorted when blown rearwardly against the firing pin, unless the firing pin face is properly constructed to prevent such distortion. To this end, I have made the striking face 32^a of the firing pin with a concave surface which substantially conforms with the normally convex head of a primer, as shown in Fig. 11. The striking point 32^b is sufficiently raised to detonate the primer, but as the primer is thrown rearwardly the entire rear face of the primer contacts with the striking face of the firing pin in such a manner as to prevent any considerable distortion of the primer, and a consequent loss of power which would be caused by such distortion. It will be remembered that the successful operation of the automatic mechanism depends upon the impulse imparted to the firing pin acting through a very short distance, and for this reason it is preferable to provide the construction of firing pin herein described in order to utilize the maximum of power imparted from the limited rearward movement of the cartridge, in the manner described.

Having thus fully described my invention what I claim as new and desire to secure by Letters Patent is:

1. The method of operating an automatic gun provided with reciprocating firing mechanism, which consists in so confining a cartridge in the firing chamber as to allow a limited rearward longitudinal movement thereof, exploding the cartridge, and utilizing the said rearward movement of the shell and the rearward movement of the primer relative to the shell to return the said mechanism to operative position. 100
2. The method of operating an automatic gun provided with reciprocating firing mechanism normally under the influence of power tending to move it toward the firing chamber, which consists in communicating to said firing mechanism the combined forces of a rearward movement of a cartridge primer relative to its shell and of a confined exploded cartridge, whereby said power is overcome and the mechanism returned to operative position. 110
3. The method of operating an automatic machine gun which consists in deriving energy from a rearward longitudinal movement of an exploded primer relative to its shell and of the exploded shell while confined in the firing chamber and utilizing said energy to actuate the automatic mechanism. 115
4. The method of operating an automatic machine gun provided with a reciprocating actuator, which consists in confining a cartridge in the firing chamber, closing the end of the firing chamber, exploding the cartridge while it is spaced from the closed end 125 130

of said chamber, utilizing a rearward movement of the exploded cartridge, and of the exploded primer, relative to the shell to drive the actuator rearwardly, and then opening the end of the firing chamber and withdrawing the exploded cartridge before the actuator has reached the limit of its rearward movement.

5. The method of operating an automatic machine gun provided with a reciprocating actuator, which consists in confining a cartridge in the firing chamber, closing the end of the firing chamber, moving the cartridge away from the closed end of said chamber, exploding the cartridge while it is spaced from the closed end of said chamber, utilizing a rearward movement of the exploded cartridge, and of the exploded primer, relative to the shell to drive the actuator rearwardly, and then opening the end of the firing chamber and withdrawing the exploded cartridge before the actuator has reached the limit of its rearward movement.

6. The method of operating an automatic machine gun provided with a reciprocating actuator, which consists in confining a cartridge in the firing chamber, closing the end of the firing chamber, exploding the cartridge while it is spaced from the end of said chamber, utilizing a rearward movement of the exploded cartridge and a further rearward movement of the primer thereof relative to the shell to drive the actuator rearwardly, and then opening the end of the firing chamber and withdrawing the exploded cartridge before the actuator has reached the limit of its rearward movement.

7. The method of operating an automatic machine gun provided with a reciprocating actuator, which consists in confining a cartridge in the firing chamber, closing the end of the firing chamber, moving the cartridge away from the closed end of said chamber, exploding the cartridge while it is spaced from the end of said chamber, utilizing a rearward movement of the exploded cartridge and a further rearward movement of the primer thereof relative to the shell to drive the actuator rearwardly, and then opening the end of the firing chamber and withdrawing the exploded cartridge before the actuator has reached the limit of its rearward movement.

8. The method of operating an automatic machine gun provided with a reciprocating actuator, which consists in causing the forward reciprocation of the actuator to confine a cartridge in the firing chamber, closing the end of the chamber, exploding the cartridge while it is spaced from the closed end, utilizing the resultant rearward movement of the exploded cartridge to drive the actuator rearwardly, causing the actuator, in its rearward movement, to open the firing chamber and withdraw the exploded car-

tridge and expelling the exploded cartridge from the gun.

9. The method of operating an automatic machine gun provided with a reciprocating actuator, which consists in causing the forward reciprocation of the actuator to confine a cartridge in the firing chamber, closing the end of the chamber, exploding the cartridge while it is spaced from the closed end, utilizing the resultant rearward movement of the exploded cartridge and a further rearward movement of the primer thereof relative to the shell to drive the actuator rearwardly, causing the actuator, in its rearward movement, to open the firing chamber and withdraw the exploded cartridge, and expelling the exploded cartridge from the gun.

10. The method of operating an automatic machine gun which consists in deriving energy from a movement of an exploded cartridge, and a further rearward movement of an exploded primer relative to its shell confined in the firing chamber.

11. A machine gun comprising automatic reciprocating mechanism operated by power derived from a limited longitudinal movement of the exploded cartridge, and a further limited movement of the exploded primer relative to the shell while the shell is confined in the firing chamber.

12. A machine gun comprising automatic mechanism operated by power derived from a combination of co-acting movements caused by the explosion of a cartridge, including a limited longitudinal movement of the cartridge shell while confined in the firing chamber, and a limited relative movement between the primer and the cartridge shell.

13. A machine gun comprising automatic mechanism operated by power derived from a combination of co-acting movements caused by the explosion of a cartridge primer and of the subsequent explosion of a cartridge, including a limited longitudinal movement of the primer relative to the shell and of a similar movement of the cartridge shell while confined in the firing chamber, and a rearward movement of said shell after the same becomes partially released from said chamber.

14. A machine gun comprising automatic mechanism operated by power derived from a combination of co-acting movements caused by the explosion of a cartridge primer and of the subsequent explosion of a cartridge, including a longitudinal movement of a part of said mechanism mounted for individual rearward movement under impulse of the recoil of the gun, and a limited longitudinal movement of the cartridge shell while confined in the firing chamber, and a further longitudinal movement of the primer relative to the shell.

15. A machine gun comprising automatic

- mechanism operated by power derived from a combination of co-acting movements caused by the explosion of a cartridge, including a longitudinal movement of a part of said mechanism mounted for individual movement under impulse of the recoil of the gun, a limited longitudinal movement of the cartridge shell while confined in the firing chamber, and a further limited movement of the primer in relation to said shell.
16. A machine gun comprising automatic mechanism operated by power derived from a combination of co-acting movements caused by the explosion of a cartridge, including a limited longitudinal movement of the cartridge shell while confined in the firing chamber, a further limited movement of the primer relative to said shell and a further movement of said shell after the same has become unconfined in said firing chamber.
17. A machine gun comprising automatic mechanism operated by power derived from a combination of co-acting movements caused by the explosion of a cartridge primer and of the subsequent explosion of a cartridge, including a longitudinal movement of a part of said mechanism mounted for individual rearward movement under impulse of the recoil of the gun, a limited rearward movement of the cartridge shell while confined in the firing chamber, a rearward movement of the exploded primer relative to the shell, and a further rearward movement of said shell after the same has become partially unconfined in said firing chamber.
18. A machine gun comprising automatic mechanism operated by power derived from a combination of co-acting movements caused by the explosion of a cartridge, including a longitudinal movement of a part of said mechanism, mounted for individual rearward movement under impulse of the recoil of the gun, a limited longitudinal movement of the cartridge shell while confined in the firing chamber, a further limited movement of the primer in relation to said shell, and a further movement of said shell after the same has become partially unconfined in said firing chamber.
19. A machine gun of the character described provided with a firing chamber having a rear retaining member which is spaced from the cartridge confined thereby, during the instant of firing while the cartridge is completely forward.
20. A machine gun of the character described provided with a firing chamber having a rear retaining member spaced from the cartridge confined thereby during the instant of firing, while the cartridge is completely forward, and a firing element extending through said member.
21. A machine gun of the character de-
- scribed provided with a firing chamber having a rear retaining member spaced from the cartridge confined thereby during the instant of firing, while the cartridge is completely forward, and a firing element extending through said closure and reciprocable mechanism adapted for engagement with said element to explode the cartridge.
22. In an automatic machine gun, in combination, a breech bolt adapted to be locked in a forward position, a firing chamber so constructed as to afford a limited longitudinal movement of the cartridge in said firing chamber while the bolt is in locked position, and means to receive energy from said limited movement of the exploded cartridge, and from a movement of the exploded primer relative to the cartridge shell, to operate the mechanism of the gun.
23. In an automatic machine gun, in combination, a breech bolt adapted to be locked in a forward position, a firing chamber so constructed as to afford a limited longitudinal movement of a cartridge in said chamber, while the bolt is in locked position, means affording a further limited movement between the exploded cartridge and the primer in relation to said cartridge while the bolt is in locked position, and means to receive energy from the movement of said exploded cartridge and primer to operate the mechanism of the gun.
24. A machine gun comprising a breech bolt having reciprocating action and adapted to be locked in a forward position, a firing chamber so constructed as to afford a limited longitudinal movement of a cartridge in said firing chamber, while the bolt is in locked position, an actuator, means in contact with said cartridge and its primer, adapted for throwing said actuator rearwardly upon explosion of the cartridge, to unlock said bolt, and a spring for returning said actuator.
25. A machine gun comprising a breech bolt adapted to be locked in a forward position, a firing chamber so constructed as to permit a limited rearward movement of a cartridge therein, a firing pin movably mounted in said breech bolt and arranged to engage the primer of and explode said cartridge, and permitting a further rearward movement of said primer, in relation to said cartridge, an actuator adapted to be thrown rearwardly by said firing pin upon explosion of the cartridge to unlock said bolt, and a spring to return said actuator.
26. An automatic gun comprising in combination with a reciprocating actuator and a firing chamber, a bolt carried by the actuator and adapted to be locked in position at the rear end of the firing chamber and to operate as a closure spaced from the contained cartridge after the latter has been projected to the limit of its forward move-

- ment, means carried by the bolt for firing the cartridge under impact of the actuator, and means carried by the actuator and bolt for unlocking the bolt after the cartridge is fired. 5
27. An automatic gun comprising a firing chamber, a reciprocating actuator, a breech bolt carried thereby, means carried by the actuator and bolt for locking the bolt in position to close the rear end of the firing chamber but spaced from the contained cartridge after the latter has been projected to the limit of its forward movement, and a firing element carried by said bolt and operable under impact of the actuator. 10
28. In an automatic gun provided with a firing chamber, a reciprocating actuator, and a breech bolt carried thereby, means carried by the actuator and breech bolt whereby the forward movement of the former will lock the latter in position to close the firing chamber, but spaced from the contained cartridge after the latter has been projected to the limit of its forward movement, and whereby the actuator may move rearwardly and, at a certain point in its rearward movement, will operate to unlock the breech bolt, and means carried by the bolt for exploding the cartridge under impact of the actuator. 15
29. An automatic gun mechanism comprising in combination a bolt for confining the cartridge in the firing chamber, said bolt leaving the cartridge free to move, a lock for said bolt, and a reciprocatory actuator adapted to move rearwardly after the firing of the cartridge, and to thereafter release said bolt. 20
30. In an automatic machine gun in combination a receiver, a reciprocatory actuator, a breech bolt having rotatable and longitudinal movement, cam connections between said actuator and breech bolt, locking members in said receiver for locking the bolt to confine a cartridge in the firing chamber, but leaving the cartridge free to move a limited distance in said firing chamber when the bolt is in locked position, and a firing pin movably mounted in said bolt and engaged by the actuator to move the cartridge away from the breech bolt. 25
31. In an automatic machine gun in combination a reciprocatory actuator, a breech bolt adapted to be locked to confine a cartridge in the firing chamber, but leaving the cartridge free to move a limited distance in said firing chamber when the bolt is in locked position, a firing pin movably mounted in said bolt and engaged by the actuator to move the cartridge away from the breech bolt, to detonate the primer, and to throw the actuator rearwardly, and means carried by the actuator for unlocking the bolt after the cartridge is fired and before the actuator has completed its rearward movement. 30
32. An automatic machine gun provided with a receiver, a reciprocatory actuator mounted therein, a breech bolt carried by the actuator and having longitudinal and rotative movement therein, said bolt being adapted to so confine a cartridge as to permit a limited longitudinal movement thereof, and means carried by the receiver for guiding the actuator in its reciprocations and for co-operating therewith in the rotative movements of said bolt. 35
33. An automatic machine gun provided with a receiver, a reciprocatory actuator mounted therein, a breech bolt carried by the actuator and rotatable therein, and adapted to confine a cartridge, while permitting a limited longitudinal movement of the latter, a fin on the bolt, means carried by the receiver for guiding said fin, and means on the bolt and actuator for rotating said bolt. 40
34. An automatic machine gun provided with a receiver and a firing chamber, a reciprocatory actuator mounted in said receiver, a breech bolt carried by said receiver and rotatable therein, said bolt being adapted to confine a cartridge in said chamber while permitting a limited rearward movement thereof, and co-operating means mounted on the bolt, the actuator and the receiver adapted upon forward reciprocation of the actuator to rotate said bolt and to lock it in position to close the rear end of the firing chamber. 45
35. An automatic machine gun provided with a receiver and a firing chamber, a reciprocatory actuator mounted in said receiver, a breech bolt carried by said receiver and rotatable therein, said bolt being adapted to confine a cartridge in said chamber while permitting a limited rearward movement thereof, and co-operating means mounted on the bolt, the actuator and the receiver, adapted upon forward reciprocation of the actuator to rotate said bolt and to lock it in position to close the rear end of the firing chamber, said means on the bolt and actuator also operating to unlock the bolt and open the firing chamber, upon rearward reciprocation of the actuator. 50
36. A machine gun comprising automatic mechanism operated by power derived from a combination of co-acting movements caused by the explosion of a cartridge, including a limited longitudinal movement of the cartridge shell while confined in the firing chamber, a further limited movement of the primer relative to said shell, and a further movement of said shell after the same has been unconfined in said firing chamber, said means also operating to hold the bolt locked during a relatively short rearward reciprocation of the actuator, but operating to unlock the bolt and open the firing chamber upon further rearward reciprocation. 55
37. A machine gun provided with firing mechanism, a magazine, and a locking bolt, 60

and also provided with a locking arm engaging said magazine and holding it in operative position, said arm carrying a portion normally preventing retraction of said locking bolt.

38. An automatic machine gun provided with a receiver containing automatically operating breech mechanism, a spring for actuating said mechanism, and a stock bracket detachably connected to said receiver

and provided with flanges preventing undesired movement of said spring.

39. In a device of the class described a firing pin provided with a striking point and a surface surrounding said point and conforming substantially with the shape of a primer to be detonated. ¹⁵

In testimony whereof I affix my signature.

JOHN C. GARAND.
